CLAIM

The ornamental design for a dispenser as shown and described.

DESCRIPTION

FIG. 1 is a perspective front and top view of a dispenser according to our new design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The solid line represents a perforated or weakened line that defines a removable portion of the dispenser.

The short broken lines shown illustrate portions of the dispenser that form no part of the claimed design.

The broken lines consisting of dot-dash lines depict fold lines that are not part of the claimed design.

The broken lines consisting of dot-dot-dash lines depict a portion of a fold line that is part of the claimed design.

(Continued)

The unshaded portions of the dispenser form no part of the claimed design.
